UNITED STATES PATENT OFFICE

148,891

DESIGN FOR A DISH

Alwin L. Suman, Sierra Madre, Calif.

Application October 12, 1946, Serial No. 133,906

Term of patent 3½ years

(Cl. D44—15)

To all whom it may concern:

Be it known that I, Alwin L. Suman, a citizen of the United States and residing at Sierra Madre, in the county of Los Angeles, State of California, have invented a new, original, and ornamental Design for Dish, of which the following is a specification, reference being had to the accompanying drawing, forming part thereof, in which:

Fig. 1 is a top plan view of a dish showing my new design.

Fig. 2 is a side elevation of said dish as when stood on end.

Fig. 3 is bottom plan view of said dish.

Fig. 4 is a side elevation of said dish when resting on the bottom thereof, and

Fig. 5 is a fragmentary sectional view of the dish shown in Fig. 1 taken on line 5—5.

I claim:

The ornamental design for a dish, substantially as shown.

ALWIN L. SUMAN.
